UNITED STATES PATENT OFFICE

2,258,233

MOTOR OPERATED CIRCUIT BREAKER
MECHANISM

Winfield A. Atwood, Yeadon, and Joseph W. Seaman, Upper Darby, Pa., assignors to General Electric Company, a corporation of New York

Original application February 23, 1939, Serial No. 257,914. Divided and this application April 24, 1941, Serial No. 390,184

4 Claims. (Cl. 200—92)

Our invention relates to motor operated circuit breaker mechanisms, and has for its principal object the provision of an improved motor operated circuit breaker mechanism that is symmetrical and compact, positive and efficient in operation, and wherein the motor actuating unit can be mounted in detachable interchangeable relation to the circuit breaker proper for ready servicing and replacement.

This application is a division of our application Serial No. 257,914, filed February 23, 1939, for "Circuit breaker operating mechanism."

In accordance with our invention, the motor mechanism, including suitable thrust transmitting structure, is mounted in a frame or support that is adapted to receive in interchangeable detachable relation the complete motor unit. The motor unit is detachably related to the thrust transmitting structure so that it can be readily interchanged or replaced as desired without disassembly of the thrust transmitting structure.

Our invention will be more fully set forth in the following description referring to the accompanying drawing, and the features of novelty which characterize our invention will be pointed out with particularity in the claims annexed to and forming a part of this specification.

Referring to the drawing, Fig. 1 is a perspective extended view, partly in section and partly diagrammatic of an electric circuit breaker mechanism embodying the present invention, and Fig. 2 is a side elevational view of the motor mechanism unit of Fig. 1.

The complete operating mechanism illustrated by way of example comprises an interchangeable motor actuating unit generally indicated at 1, a main operating toggle 2, and a tripping device for the toggle mechanism generally indicated at 3. The electric circuit breaker to be operated is shown at 4. Certain features of this mechanism are disclosed and claimed in Patent No. 2,152,453, issued March 28, 1939, to W. A. Atwood and G. Rudolph for "Operating mechanism," and assigned to the same assignee as the present invention.

The actuating unit 1 comprises a reciprocally guided plunger or crosshead 5 that is connected through a slotted link 5' and cam 7 to the motor operating unit 6. The motor unit may be of the type disclosed and claimed in Linde Patent No. 2,034,145, granted March 17, 1936, for "Operating mechanism" wherein an automatic brake generally indicated at 6' is interposed with respect to the cam shaft 7' and the motor proper. Suitable reduction gearing for the cam shaft is

also generally indicated at 6''. The link 5' carries a cam follower or roller 8 for coacting with the cam 7, and the link is slotted at 5'' for receiving the cam shaft 7'. This not only provides 5 guiding means for the link 5' but makes the design more compact. The link 5' and the crosshead 5 are detachably interconnected as by a removable pin 2' so that the cam shaft and motor assembly can be removed without disassembly of the linkage 2.

Referring more particularly to the thrust transmitting structure, the main operating toggle 2 comprises a pair of interconnected links 11 and 12 that are operatively connected to the 15 crosshead 5 by a link 9 at the toggle joint or knee 10. The link 9 is detachably connected to the crosshead 5 by a pin 9' that extends beyond the crosshead for a purpose hereinafter described. The link 11 is connected to a guide link 13 having a fixed pivot at 14, and the link 12 to a crank 15 that is rotatable on a shaft 16.

The crank 15, which is operated by the toggle 2 in response to operation of the actuating unit, i. e., by rotation of the cam 7, comprises a generally U-shaped member having substantially parallel sides 15' through which the shaft 16 extends, interconnected by an integral transverse strip 15'' extending parallel to the shaft. The crank at one side is provided with a cam surface 17 adapted to coact with a circuit breaker crank 18 which is rigidly connected through a rotatable countershaft 19 to the movable arm 20 of the circuit breaker 4. When the crank 15 is rotated clockwise as viewed by straightening of the main toggle 11—12 in response to elevation of the crosshead 5 by the cam 7, the cam face 17 bearing on the roller 18' of the breaker crank rotates the breaker shaft 19 in counterclockwise direction whereby the movable contact structure 20 of the circuit breaker 4 is moved into contact engagement with the stationary contact structure 21. This movement, or working stroke of the breaker structure 20 is generally in opposition to spring pressure tending to bias the breaker to open circuit position.

For the purpose of holding the toggle 11—12 at the pivot 13' in thrust-transmitting position with respect to the crank 15 the toggle guide link 13 is related to suitable latching and tripping means 50 comprising a link 22 connected to the toggle pivot 13' and to a latch 23 having a fixed pivot at 24. The members 22 and 23 are suitably interconnected as at 25 for insuring a force-reducing connection. Coacting with the latch 23 is a rotatable tripping shaft 26 to which is secured

a detent member 27 adapted to engage the latch 23 at its notched portion 28.

In the position shown collapse of the toggle 11-12, that is, counterclockwise rotation of the toggle pivot 13' and dropping of the knee joint, is restrained by the latch 23 and detent 27. Tripping movement, that is, counterclockwise rotation of the tripping shaft 26, effects release of the latch 23 so that it is free to rotate counterclockwise for releasing the pivot 13' and permitting opening movement or collapse of the toggle.

In the closed circuit or restraining position shown the tripping means 3 is latched and the toggle is held in an underset extended position by a prop 29 adapted to support the knee 10 of the toggle. The prop is shown as being secured to a rotatable shaft 30 that is resiliently connected by a spring 31, as illustrated, to the tripping shaft 26 so as to facilitate resetting of both the prop and the latching means after a circuit opening or releasing operation of the mechanism.

Referring more particularly to the tripping means, the tripping shaft 26 is provided with an offset portion or arm 32 for coacting with a tripping means 33 that is shown as a solenoid energized from a control source through a switch 34. The member 32 may also be engaged by manual tripping means indicated at 32'. A conventional overload tripping coil 35 shown as energized from the main circuit at 4' may also coact with the tripping shaft at 36. When the breaker is closed as shown in Fig. 1 and the cam 7 is in the position shown, tripping can be accomplished by rotating the tripping shaft 26 counterclockwise by any of the means described.

The breaker crank 18 is also connected to the crank 15 by means of a compression spring 37 guided on a member 38 engaging one end of the crank 15' and having a guided sliding connection at 39 with an arm of the crank 18. In the closed circuit position shown the spring 37 is under compression so that immediately upon release of the tripping latch, opening movement of the toggle 11-12 is accelerated by the stored spring energy, resulting in rapid movement of the cam surface 17 away from the roller 18'. The circuit breaker crank 18 is also acted upon throughout the breaker opening stroke by the spring 37 tending to accelerate separation of the contacts 20 and 21. During the closing operation when the crank 15 is rotated clockwise the spring 37 is placed under compression by reason of the comparatively long lever arm of the crank 18 acting in the opposite direction on the spring.

When the toggle 11-12 is released in response to a tripping operation, the toggle pivot 13' is free to rotate counterclockwise about pivot 14 thereby causing shifting of the toggle knee 10 from the end of the prop 29 and permitting dropping of the knee and opening movement of the toggle. The prop 29 is suitably shaped, as illustrated, for permitting free movement of the toggle knee 10 alongside the prop. Emergency manual closing is of course possible by lifting the crossheads by suitable means.

The resilient connection 31 between the trip shaft 26 and the prop shaft 30 biases the tripping detent into latching engagement after the latch 23 in dropping pushes down on and passes by the latch detent 27, the latter snapping into reset position due to the bias of spring 31. At the same time the spring 31 exerts a counterclockwise bias on the prop 29 urging it against the side of link 9 so that when the links 11 and 12 are raised to toggle position in a subsequent clos-

ing operation, the prop 29 is snapped beneath the toggle knee 10 to hold the mechanism in closed position independently of the actuating means. A stop member 29' is provided for preventing movement of the prop beyond the toggle knee.

It will therefore be noted that the mechanism is trip-free in operation since at any time during the closing stroke, release of the toggle pivot 13' in response to a tripping operation causes freeing of the toggle and opening of the circuit breaker. The opening speed is very rapid due to the fact that the main toggle can simply shift laterally off the prop 29 to open the breaker, since complete collapse of the toggle is not required until the linkage is to be reset. Actual breaking of the toggle is therefore unnecessary to initiate the opening movement. In the case of trip-free operation as the crosshead 5 is elevated by the motor operated cam 7, the toggle remains in the extended position shown during the opening stroke. The resetting operation then takes place as the crosshead is lowered when the roller 8 drops to the "low" point of the cam 7 and the latch 23 drops to its latching position. This resetting operation is also followed for normal tripping. The circuit breaker can, if desired, have separate means such as springs for normally biasing the same toward open circuit position.

The mechanism proper above described, apart from the motor actuating unit, is permanently mounted in a frame 44 as shown by Fig. 2 comprising a pair of spaced side plates suitably secured as indicated to a support or panel 45. The various shafts and pivots of the mechanism can be journaled in the side plates so that the mechanism proper is a compact and integral unit.

Referring now to the motor actuating unit, it includes a compact casting or housing 46 for the reduction gearing and also for supporting the motor base at 47. Fig. 2 illustrates more specifically the application of the motor operating device and unit to the above described mechanism. As illustrated, the electric motor actuating unit comprises a unitary structure that is secured at 48 to the mechanism frame 44. The securing bolts or the like at 48 can conveniently be the same bolts for securing together the parts of the housing 46. The pins 2' and 9', which extend through and beyond the crosshead at opposite sides thereof are guided in slots 47 which are formed in both side plates of the frame 44. The slots are open at the top so that the crosshead can readily be inserted in the frame.

As illustrated by Figs. 1 and 2, the actuating unit includes an electric motor 50, the rotor shaft 51 of which is vertically positioned and provided with a worm drive 52 for coacting with a worm gear 53 that is secured to the cam shaft 7'. The cam 7 mounted on the shaft 7' is of suitable design for applying the breaker closing force and is actuated in clockwise direction as indicated upon energization of the motor 50. The cam and its associated shaft and operating gears included in the casing 46, together with the motor and self-contained brake unit indicated at 6', are mounted as a complete and detachable unit on the frame 44.

In a motor operated cam mechanism of the character above described, the motor is energized for predetermined rotation of the cam, after which the motor is deenergized and the rotating parts brought to a quick stop by the

automatic brake indicated at 6' as described in the aforesaid Linde patent. The cam follower or roller 8 rides from the "low" point of the cam 7 to the "high" point, thereby raising the crosshead 5 and closing the breaker at 4. As illustrated, the slotted link 5' is guided for reciprocal rectilinear movement both by the cam shaft and by the guided crosshead 5 so that the cam follower is limited to reciprocal rectilinear movement.

When the breaker is closed, the cam 7 is rotated somewhat beyond its "high" point before being checked by the brake as shown by both Figs. 1 and 2. The breaker in this position is held closed by the prop 29. Therefore, when the breaker is tripped, the crosshead 5 is free to drop and the linkage is thereupon automatically reset in the manner previously described. When the motor actuating unit is to be removed for servicing, inspection or replacement, the bolts 48 are simply unloosened and withdrawn from the frame at the three points indicated. The pin 2' is then withdrawn freeing the link 5' so that the complete actuating unit including the cam can be lifted from the frame without disturbing the thrust-transmitting mechanism or the circuit breaker.

It should be particularly noted that the motor mechanism above described is rugged and compact and symmetrical with respect to the actuating force. By avoiding unnecessary and complicated operating linkage and associated structure, the actuating force is effectively and efficiently applied, thereby securing a more compact and efficient design for a given power rating.

It should be understood that our invention is not limited to specific details of construction and arrangement thereof herein illustrated, and that changes and modifications may occur to one skilled in the art without departing from the spirit of our invention.

What we claim as new and desire to secure by Letters Patent of the United States is:

1. Circuit breaker operating mechanism comprising a supporting frame, thrust transmitting means mounted in said frame, a member guided for reciprocal rectilinear movement in said frame for actuating said thrust transmitting means, and an electric motor actuating unit adapted to be mounted in said frame in detachable interchangeable relation thereto, said unit including a cam disposed in operative relation to said rectilinear guided member.

2. Circuit breaker operating mechanism comprising a supporting frame having spaced side members, thrust transmitting means mounted in said frame between said members, a member guided for rectilinear movement between said side members for actuating said thrust transmitting means so as to close the circuit breaker, and an electric motor actuating unit including a cam adapted to be mounted in said frame between said side members in detachable interchangeable relation thereto, said cam being operatively related to said guided member so that rotation of said cam to the high point thereof is effective to close said breaker and rotation of said cam to the low point thereof permits resetting of said thrust transmitting means, and means for readily detaching said motor actuating unit with respect to said frame whereby said unit can be lifted from the frame independently of said thrust transmitting means.
3. Circuit breaker operating mechanism comprising a supporting frame, thrust transmitting means mounted in said frame, a crosshead member guided for reciprocal movement in said frame for actuating said thrust transmitting means, an electric motor actuating unit including a cam and cam shaft operatively connected to the motor adapted to be mounted in said frame in detachable interchangeable relation thereto, a cam follower, and a link interconnecting said crosshead member and cam follower, said cam shaft extending through an aperture in said link and guiding said link so that said cam follower is operated substantially in a rectilinear path for actuating said crosshead member.
4. Circuit breaker operating mechanism comprising a supporting frame, thrust transmitting means connected to the circuit breaker mounted in said frame, an electric motor actuating unit including a motor, reduction gearing, a cam and cam shaft adapted to be mounted in said frame in detachable interchangeable relation thereto, said unit including securing means for detachably connecting said unit to said frame so that said unit can be lifted from said frame without disassembling said thrust transmitting means, and means operatively relating said cam to said thrust transmitting means for closing the circuit breaker.
